UNITED STATES PATENT OFFICE.

CHARLES H. DANA, JR., OF WEST LEBANON, NEW HAMPSHIRE.

MACHINE FOR STRINGING TAGS.

SPECIFICATION forming part of Letters Patent No. 356,101, dated January 18, 1887.

Application filed June 14, 1886. Serial No. 205,186. (No model.)

To all whom it may concern:

Be it known that I, CHARLES H. DANA, Jr., a citizen of the United States, residing at West Lebanon, in the county of Grafton and State 5 of New Hampshire, have invented certain new and useful Improvements in Machines for Stringing Tags; and I do declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 The object of my invention is to provide an improved machine for stringing tags, the knot fastening the string being what is commonly called a "slip-noose;" and my invention consists in details of construction described below, and pointed out in the claims.

In the drawings, Figure 1 is a side elevation. Fig. 2 is a plan view below line x x , Fig. 1, the cam-lever omitted, showing the rigid slide-hook, the toggle-arm hook, and the 25 pincher-shears starting from the left to carry the twine in two loops or three parallel courses to the tag-plate on the right. Fig. 3 is a like view, the pincher-shears, the slide-hook, and toggle-arm hook having carried the twine 30 loops partly above and below the tag-plate, the pincher-shears being about to release one end of the twine in order that it may be carried up through the hole in the tag by the grip rod and hook to form a loose knot, (see 35 Figs. 7 and 8,) and the hooks being about to move out of said loops as the slide travels to the left again. Fig. 4 is a sectional side elevation showing the position of the parts when the slide has nearly completed its left throw, the 40 pincher-shears gripping the twine to tighten the knot, the twine being severed just after the slide reverses, when the parts are as in Fig. 2. Figs. 5 and 6 are sectional views of opposite sides of the pincher-shears. Figs. 7, 8, 9, 45 and 10 are sectional perspective views of the tag-plate and tag, showing different stages in the formation of the knot. Fig. 11 is a detached view of the hook and grip-rod. Fig. 12 is a plan view of the twine-looping devices, 50 most of the machine being broken away and the slide having moved to the right of the position shown in Fig. 2. Fig. 13 is an end view

looking toward the hooks a^3 a^5 , when as shown in Fig. 12, certain parts of the machine being removed. Fig. 14 is a transverse section of 55 the pincher-shears removed.

Like letters refer to like parts.

A is the frame. At one side of it is a way, B, and its top is inclined toward the frame. (See b , Figs. 2, 3, and 11.) On this 6c. incline rests a slide, C, whose bottom is correspondingly inclined.

C' is the drive-wheel on the end of shaft C², journaled in the frame. (See Fig. 2.) From a pivot, a, on said wheel the pitman D extends to the slide, a headed bolt, a', passing through the pitman, the washer a², and the slide, and it will now be seen how the slide is moved back and forward on the way. To the outer side of the slide (see Figs. 1 and 2) is 70 screwed a right-angular strip, C³, the horizontal part of which is above the top of the slide and terminates in a hook, a³ bent slightly downward to easily take under the twine or draw out of it. At a⁴ there is pivoted to the 75 top of the slide and under hook a³ a toggle-arm, C⁴, provided with a hook, a⁵, for taking over the twine, (see Fig. 2,) and jointed by pin a⁶ to toggle-arm C⁵, which is pivoted to a fixed center, C⁶, on the frame, and guides the arm 80 C⁴ in its horizontal play.

C' is the twine-spool, from which the twine passes about one of the pins b' b' and under the ring-shaped weight or tension C⁷. Thence it passes through the raised guide b² on arm 85 C⁸, and through hole b³ in arm C⁴, the free end being firmly gripped by pincher-shears E.

Referring to Figs. 1, 5, and 6, the gripping and shearing device will be described.

E' is the cutting-blade, pivoted between a 90 shear-plate, E², and a grip-plate, E³, the latter being at a higher level, and having its top rounded at d. The blade E' is beveled above the cutting-edge, (see d', Fig. 5.) Therefore when the blade descends the twine will be 95 firmly gripped between the edges d d'; but just after the slide starts on its right-hand throw the blade descends to the top of the shear-plate E² and severs the twine, leaving, however, the end of the twine running from the 100 spool still gripped between the blade and the plate E³, (see Fig. 4 and also Fig. 2,) where the twine has just been cut. The shear action will be further referred to in the descrip-

tion of the mode of operation. The pincher-shears travel with the slide, and may be attached to the inner side of it by bolting the above plates thereto; but it is not necessary to show this obvious fastening. To raise and lower the blade, a link, F, is pivoted at d^2 , and also at d^3 to the end of the angular extension F' of the pitman. (See Figs. 1 and 3.) Therefore the throw of the pitman governs the grip 10 and cut of the blade E.

G is the feed or tag plate. It has two folded-over edges, G' G², (see Fig. 2,) which serve as guides as the tags are fed under the corner, and also prevent the twine from touching and 15 displacing them. As these edges are beveled toward the working parts and incline upward, the twine cannot foul. The plate G has a U-shaped slot at f (see Fig. 2) to permit the descent of the grip-hook through the eyelet of 20 the tag, which operation will be described later on, and underneath is provided with a stop, G³, having a shoulder, g, for arresting the twine extending from the pincher-shears to the toggle-arm hook a⁵, when the parts assume 25 the position of Fig. 3, until the grip hook and rod descending take hold of the twine and then draw it up through the tag, the shears releasing their grip just before the latter operation.

The mechanism for operating the grip hook 30 and rod will now be described. To the frame at e, (see Fig. 2,) is pivoted the bent arm H. At e' (see Fig. 1) is pivoted a cam-lever, H', the lower bent end of which enters a slot, e², (see Fig. 3,) in the slide C, and is pivoted 35 therein by the bolt a' before mentioned. It will now be seen that as the slide moves back and forth the lever H' will raise and lower arm H. The end of said arm nearest the lever is vertically bored out and screw-threaded 40 about half-way down. In this bore is inserted a hollow threaded sleeve, H², which is thus rendered adjustable up or down. This sleeve terminates below in a rigid hook, h. Playing in the hollow of the sleeve is grip-rod H³, attached by a pin, i, to lever H⁴, slotted at i', and pivoted to arm H at i'. Extending from arm H through lever H⁴ is a headed pin, K, surrounded by a spiral spring, k, whose normal action is by pressing on lever H⁴ to hold 45 down the grip-rod H³ to clutch the twine between the end of said rod and the barb of hook h. About the pivot e' (see Figs. 1 and 4) the lever H' is formed in the shape of a cam, L, and on the back side of this are two diagonally-opposite pins, l' l". Between the cam and arm H there is attached to pivot e' a dog, M, having a shoulder, m, and on lever H⁴ is a roller, N, engaging with the cam and allowing the spring to lower the grip-rod H³, or lifting said rod when pin l has forced the dog under the roller, the lever H⁴ being lifted up against the spring (see Fig. 4) until the pin l", returning to the position in Fig. 1, has knocked the dog back again. It may be stated that the 50 dog holds up lever H⁴ during a large part of the down movement of arm H, and that the

down throw of rod H³ into hook h is of comparatively short duration—that is, during the stringing of the tag and the loosest stage of the knot.

A description of the operation will show how the parts act at different stages, and is as follows: The knot is begun when the slide has just started on its right throw. (See Fig. 2.) The hook a⁵ is under hook a³, and as the slide moves hook a⁵ catches over the twine and hook a³ under the twine, nearer hole b³, and this operation separates the twine into two loops or three parallel courses. The slide having reached its right throw, (see Fig. 3,) the stretch 80 of twine from hook a⁵ to hook a³, being highest, is carried above the corner of the feed-plate, while the twine from hook a³ to hole b³ is carried just under the plate, but above the shoulder g of stop G³. The twine running from hook a⁶ to the pincher-shears, being lowest, strikes shoulder g, where it is in position to be clutched by the grip-hook h, (see Fig. 1,) which descends through the slot of the feed-plate and the eyelet of the tag after the other courses of 85 twine pass under said hook. The sliding grip-rod now descends by the action of the cam L and the spring k on the lever H⁴ and holds the twine in the barb of the hook h. The pincher-shears now open and release the free end of 90 the twine, and it is carried up through the tag-eyelet by the rising hook h. As the hook is moved up by arm H the hooks a³ and a⁵ back out of the twine-loops, the slide having started on its left throw, leaving said loops to be drawn 95 away from the feed-plate to form a loose knot opposite the slot f by the drawing up through the tag-eyelet of the twine carried by hook h. (See Figs. 4, 7, 8, 9, and 10.) As the slide continues its left throw the hook a⁵ swings 100 through the open shears, leaving the twine coming from the spool trailing back through the shears to the tag, the ring-weight C⁸ giving enough tension to draw the knot nearly 105 tight. When the parts are as in Fig. 4, the 110 rising rod H³ has just freed the twine from hook h and the blade E' has gripped the twine between the edges d' d, (see Figs. 5 and 6,) and at this point the run of the twine through the shears is stopped and the knot begins to further tighten. When the slide reaches its left 115 throw, the shears draw the knot tight. As the slide starts again on its right throw the twine slackens, and is cleanly cut by the blade E' and the top of the shear-plate E², when the 120 tag may be removed and another fed in before hook h reaches the feed-plate. After the twine is cut the end of it extending back to the spool is still held by the gripping parts of the shears (see Fig. 2) where the twine has just been cut, 125 and is about to be carried to the feed-plate again, as in Fig. 3. Referring again to the fact that the dog M holds up lever H⁴ during a larger part of the down motion of arm H, or until pin l" knocks the dog away from roller N, I would say that this is important, as it gives 130 ample time for withdrawing the tags, and I

also consider it important to good work that the final strain to tighten the knot should be on the twine drawn back to the shears.

Having fully described my invention, what 5 I claim, and desire to secure by Letters Patent, is—

1. The combination, with the moving slide operated substantially as shown, of the pincher-shears, the twine-looping hooks, the feed-plate, 10 and devices, substantially as described, for drawing the free end of the twine up through the plate and eyelet of the tag, as set forth.

2. The combination, with the slide, of the pitman, the pincher-shears, the twine-looping 15 hooks, the feed-plate, the grip-hook, and the grip-rod, operating, substantially as shown, in conjunction with said hook to draw the twine through the plate and tag and to release the twine before the shears tighten the knot, as set 20 forth.

3. The combination, with the slide having means, substantially as shown, for gripping and looping the twine, of the cam-lever operated by the slide, the arm pivoted to said lever 25 and having a depending hook, a lever pivoted to the arm, a grip-rod raised and lowered in conjunction with said hook, substantially as described, and the feed-plate provided with a slot and a subjacent stop, as set forth.

30 4. The combination, with the slide provided with devices for gripping and looping the twine, substantially as shown, of the cam-lever having a dog and oppositely-arranged pins, the arm provided with a hook and pivoted to said lever and the frame, the lever pivoted to the top of the arm and provided with a roller, the spiral spring, the grip-rod moving in conjunction with said hook, and the feed-plate, having a slot and subjacent 35 stop, as set forth.

5. The combination, with the twine-spool, of the ring-weight and the guide-pins, the toggle-arm C³, pivoted to a fixed center, the toggle-arm C⁴, pivoted to the slide and arm C⁵ and provided with opening b³ and hook a⁵, the 45 slide having pincher-shears and hook a³, the feed-plate, and devices, substantially as shown, for drawing the free end of the twine through the eyelet of the tag, as set forth.

6. The combination, with the feed-plate G, 50 having folded-over edges G¹ G², slot f, and shouldered stop G³, of the hook h and grip-rod H³, and the slide C, provided, substantially as shown, with attached devices for gripping, looping, and carrying the twine to said plate, 55 as set forth.

7. The combination, with the drive-wheel, of the pitman, the slide provided with attachments, substantially as shown, for gripping, looping, and carrying the twine, the way B, 60 the cam-lever H¹, pivoted in the slide, the arm H and its hook h, the lever H⁴, operated substantially as shown, the grip-rod H³, and the feed-plate G, as set forth.

8. The combination, with the pitman, of the 65 slide and the pincher-shears operated in connection therewith, substantially as shown, to grip the twine during the left throw of said slide, to tighten the knot and to sever the twine just after the right throw begins, as set forth. 70

9. The combination, with the slide, of the grip and shear plates, the blade pivoted between them, the link, the pitman, and the drive-wheel, as set forth.

In testimony whereof I affix my signature in 75 presence of two witnesses.
